DESIGN FOR A TABLE

Leonard A. Cutrow, Los Angeles, Calif.

Application October 3, 1945, Serial No. 122,475

Term of patent 3½ years

(Cl. D33—14)

To all whom it may concern:

Be it known that I, Leonard A. Cutrow, a citizen of the United States, residing at Los Angeles, in the county of Los Angeles, State of California, have invented a new, original, and ornamental Design for Table, of which the following is a specification, reference being had to the accompanying drawing, forming a part thereof, in which:

Fig. 1 is a perspective view of a table showing my design; and,

Fig. 2 is an end elevational view thereof.

The table shown is made of transparent plastic.
I claim:

The ornamental design for a table, substantially as shown and described.

LEONARD A. CUTROW.
